Primary Examiner — John Windmuller*Assistant Examiner* — Steven J Czyz(74) *Attorney, Agent, or Firm* — Dunlap Bennett & Ludwig PLLC(57) **CLAIM**

The ornamental design for an automobile seat belt holder, as shown and described.

DESCRIPTION

FIG. 1 is a perspective view of an automobile seat belt holder, showing my new design;

FIG. 2 is a top plan view thereof;

FIG. 3 is a bottom plan view thereof;

FIG. 4 is a front elevation view thereof;

FIG. 5 is a left side elevation view thereof, the right side elevation view being a mirror image thereof;

FIG. 6 is a rear elevation view thereof; and,

FIG. 7 is a rear elevation view thereof shown in use.

The broken lines depict environment and portions of the article that form no part of the claimed design.

1 Claim, 3 Drawing Sheets(56)
